UNITED STATES PATENT OFFICE.

WILLIAM E. JACOBS, OF COLUMBUS, OHIO.

WHEELED ROAD-SCRAPER.

SPECIFICATION forming part of Letters Patent No. 350,136, dated October 5, 1886.

Application filed March 5, 1886. Serial No. 194,152. (No model.)

To all whom it may concern:

Be it known that I, WILLIAM E. JACOBS, a citizen of the United States, residing at Columbus, in the county of Franklin and State of Ohio, have invented certain new and useful Improvements in Wheeled Road - Scrapers; and I do hereby declare the following to be a full, clear, and exact description of the invention, such as will enable others skilled in the art to which it appertains to make and use the same.

My invention relates to road-scrapers mounted on wheels; and it consists of certain novel constructions of parts as will be hereinafter fully described and specifically claimed, whereby the manipulation of the scraper is greatly facilitated, as will be seen.

In the accompanying drawings, Figure 1 is a side elevation of my scraper as it appears when loaded and being moved to the place for dumping. Fig. 2 is a side elevation of the same as it appears after being dumped and while being moved back for another load or being transported. In Figs. 1 and 2 the wheel in front of the observer is removed in order to better expose the mechanism concealed by it. Fig. 3 is a side elevation of my scraper in the act of scraping, showing a checking mechanism of the bowl by breaking away such parts as were in front of it. Fig. 4 is a view of Fig. 1, partly in plan and in section.

The letter A in the drawings represents the bowl, B an axle, C wheels, and D a tongue, of a road-scraper. The bowl A is suspended by means of rigidly-attached hangers a to the inner or cranked portion, b, of the axle B, around which portion it is swung into the required positions by means of handles a' and levers and other parts, as will now be described.

A lever-frame, E, of forked shape, is pivoted by means of its two arms, e, to the bowl A at a'. The arms e extend a suitable distance beyond the pivots a', and near their terminations are provided with a draft-bail, F, which is suitably hooked or otherwise flexibly joined to the end portions of said arms. A draft-rod, f, is connected with the bail F for the purpose of attaching what is called a "snatch-team." This draft-rod is suspended in a suitable ring-pin, f', by the tongue D. The rear portion of this tongue is provided with braces d d, which extend rearward along

the sides of the bowl to which they are pivoted at d d'. Said pivots being located near the top of the bowl and standing very near to the axle-spindles b' b', and nearly on the same horizontal plane of said spindles when the bowl is in the raised horizontal position shown in Fig. 1, serve a very important purpose—viz., by being thus located the tongue can be set high and connected far back on the bowl, and thus in dumping the load it is easy to turn up the bowl when the edge thereof engages with the earth. Near the pivots a' the braces d are provided with pins or lugs d' d', and near these pins the arms e e of the lever-frame are provided with lugs e' e', which engage with the said pins when the bowl is used for scraping, the pins d' d' and lugs e' e' preventing the bowl from turning over while it is being filled by locking the bowl to the tongue-braces d d, this being effected by the lugs e' e' on lever-frame E standing over and engaging with the pins d' d' on tongue - braces when the bowl is down and lever-frame up, as shown in Fig. 3 of the drawings. The pivots d' d' serve also to support two arms, g g, of an end - gate, G, by which the open front of the bowl A is closed, while the bowl is being transported in its elevated position, as shown in Fig. 1. The arms g g are provided with gutter-shaped lugs g' g', which extend horizontally over the braces d d and lugs e' e', and have vertical laps g' g'. The arms e, near the wheel-axles b' b', are provided with links I, whereby they are connected with said axles. The end portions of the pivots a' a' and d' d' are steadied by ordinary brackets, J, which are suitably fastened to the sides of the bowl A. The central part or handle, e'', of the lever-frame E is provided with a double pawl, K; having a fulcrum, k, handle k', upper hook, k'', and lower hook, k''. The lower hook, k'', engages with a suitable lug, a'', on the rear side of the bowl A, and thus prevents the bowl from tilting backward. The upper hook, k'', engages with a fixed hook, l, on a suitable standard, L, of the tongue D, when the lever-frame E is turned up into a vertical position, as seen in Fig. 2. In this position the lever-frame holds the bowl A by means of the said hook k'', away from the ground, as seen in Fig. 2, and the hook k'' may be employed as a further means for holding the bowl in said vertical position, and thus adjusted the road-

scraper is moved from place to place by an ordinary team attached to the pin D'.

When the bowl is to be used for scraping, the lever-frame E is disengaged from the standard L by unlocking the upper hook, h^2 , from the hook l , and said frame is turned down with the bowl, and the bowl is turned up until the pins d^2 touch the lower surfaces of the lugs e' , whereby the bowl is lowered sufficiently to enter the ground a suitable depth, as illustrated in Fig. 3. At this stage a snatch-team is attached in a suitable manner to the front end of the draft-rod f in order to apply additional draft-power to the road-scraper. When the bowl has entered the ground, the operator controls and guides it by pressing down the bowl with one hand on a handle, a' , and holds up the lever-frame E with his other hand, thereby causing the pins d^2 d^2 to be held in firm connection with the lugs e' e' , as shown in said Fig. 3, and the bowl A to remain in a steady position. While the parts were being adjusted to the position described and shown, the lugs g^2 g^2 of the lugs g' g' were caused to come in contact with the lugs e' e' and be elevated from their normal position shown in Fig. 1, and the end-gate G to be thrown up so as to permit the scraped or loosened earth to freely enter the bowl A. When the bowl A is filled the lever-frame E is turned down, swinging on the links I, and by means of pivots a^2 a^2 lifting the bowl A from the ground, and causing the hangers a a and bowl to be lifted by moving the wheel-axles b' b' toward said hangers, thereby elevating the cranked portion b of the axle B to which said hangers are attached. By this elevation of the bowl A the gate-arms g and tongue-braces d assume a parallel position, permitting the lugs g' to descend and the end-gate G by its weight to also descend and close up the bowl A. The snatch-team is now unhitched from the road-scraper and only the permanent team used for moving the filled bowl to the place of dumping its load. On arrival at the place of dumping the operator raises the lever-frame with the bowl locked thereto until the cutting-edge a' of the bowl takes a hold in the ground, whereupon, the ground serving as a fulcrum for the bowl and lever-frame, they are pulled over by the draft of the team. As soon as the lever-frame E is raised for the purpose of dumping, the lugs g' of the end-gate G are moved up by the braces d of the tongue D, and they hold up said end-gate, so as to permit the contents of the bowl to freely and entirely pass out from the bowl. The operator now turns the lever-frame, with the bowl, farther forward or toward the standard L until the hooks l and h^2 become interlocked and the road-scraper is adjusted, as shown in Fig. 2, for return to the place of scraping, and repeating the above-described operation.

It is not essential that the latch h^2 be engaged with the lug a' of the bowl when in the position shown in Fig. 2, as the bowl cannot turn back under ordinary circumstances, so

long as the catch h^2 is engaged with the hook l of the standard L.

The end-gate can be easily removed, if desired, and again as readily attached, it especially being useful when the machine is employed in digging sandy or dry soil liable to run or spill out.

The wheel-axles b' , as shown in Fig. 4, are provided with sleeves M and flanges m , shrunk upon them, the flanges m being let into the wheel-hubs c. These sleeves can be more readily constructed separately from and shrunk upon the crank-axle than wrought upon said axle, and they are important for the purpose above stated, while they serve as wearing-washers for keeping the links I of the scraper mechanism from rubbing on or against the wheel-hubs, in order to prevent sand and mud from entering between the bearings of the wheels and sleeves, which are lined or bossed in the usual manner.

It will be seen that in my road-scraper the power of the snatch-team is utilized in greatly assisting the operator in lifting the loaded bowl, and thereby doing away with an extra man, whose services are necessary with road-scrapers of ordinary construction. When the parts are in the position shown in Fig. 3, there is usually in practical machines a slight degree of play allowed between the pins d^2 and lugs e' , in order that the operator may adjust the bowl to the most suitable inclination for effectually cutting the ground and filling the bowl. It will also be seen that in providing for hitching the snatch-team to the front ends of the lever-frame E and beyond its pivots a^2 the labor of the operator is lessened in the filling of the bowl and the lifting of the same, because the draft of the team works in an upward direction upon the pivots a^2 , and affords leverage below the pivots for lifting the bowl, which leverage is acted upon by the draft of the snatch-team. By pivoting the tongue separately to the bowl and near the top thereof, the dumping of the bowl is facilitated, because while the operator raises the handles a' the pivots d' of the bowl and the wheel-axles stand nearly in a horizontal line, and thus the draft of the team causes only a very slight resistance to the raising of said handles until the front of the bowl is engaged with the ground as a fulcrum, when the new leverage thus gained enables the team to pull the bowl over as far as needed. Another advantage over other known constructions results from the employment of the lugs e' e' and pins d^2 d^2 , whereby the position of the bowl is rendered steady while scraping or gathering a load, and, furthermore, the end-gate being automatic in its operation adjusts itself to the angle of the bowl. Thus when the bowl is entered into the ground the end-gate rises and leaves an opening for the entrance of the earth into the bowl, and when the bowl is horizontal this end-gate forms a closing end piece, and during the dumping operation it will stand wide open.

With the double pawl K and lever-frame E

the bowl can be steadied in its two main positions, as described, thereby rendering the management of the bowl comparatively easy to the operator.

5. What I claim is—

1. In a wheeled road-scraper, the combination of the crank-axle B, hangers a, pivoted links I, suspended bowl A, lever-frame E, and tongue D, the pivotal connections of the lever frame and tongue being near the top of the bowl and nearly on the same horizontal plane, substantially as and for the purpose described.
2. In a wheel-scraper, the combination of the crank-axle B, hangers a, pivoted links I, lever-frame E, a suspended bowl, A, having pivots d', located near the top edge of the bowl, and a tongue, D, pivoted at d' to the bowl, substantially as and for the purpose described.
3. In a wheeled road-scraper, the combination of a cranked axle, B, a suspended bowl, A, a lever-frame, E, pivoted to the bowl A at a', and a draft-bail, F, for a snatch-team attached to lever-extensions of the lever-frame beyond the pivots a', substantially as and for the purpose described.
4. The combination of the bowl A, having pivots d' a' with the tongue-braces d, having pins d'', and the lever-frame E, having lugs e', substantially as and for the purpose described.

5. The automatic end-gate G, having lugs 30 g', in combination with the bowl having pivots d', and with the lever-frame E, having lugs e', substantially as described.

6. The combination of the swinging bowl A, having lug a', the lever-frame E, having double 35 pawl K, link I, axle B, and the tongue-standard L, having hook l, substantially as and for the purpose described.

7. The combination of the cranked axle B, tongue-standard L, having hook l, the swinging bowl A, and lever-frame E, having hook l', substantially as described.

8. The cranked axle B of a wheeled road-scraper, having sleeves M, with flanges m secured removably upon its spindle-arms, in 45 combination with the links I, and wheels C, having hubs with counterbores around their eyes at their inner ends for the close seating of the flanges m, substantially as and for the purpose described.

In testimony whereof I affix my signature in presence of two witnesses.

WILLIAM E. JACOBS.
